METHOD AND APPARATUS FOR PROPORTIONALLY MIXING A PETROLEUM OIL WITH A LIQUID REAGENT

Wright W. Gary, Los Angeles, Calif.

Application January 6, 1930. Serial No. 418,816

4 Claims. (Cl. 196—45)

My invention relates to an apparatus for proportionally mixing fluids, such as liquids with liquids and gases with liquids, and for accomplishing it with reasonable accuracy.

5 The proper proportioning of oil and acid in the treatment of petroleum is important for two reasons. First, when treating in a continuous system, if the acid is not uniformly applied, periods elapse when over treatment occurs, causing 10 a waste of acid and subsequent absorption of oil, and second, periods elapse where under treatment occurs, giving the composite treated oil an inferior quality. In other words, periods of over treatment do not counterbalance the periods of under 15 treatment.

The prevalent practice is to use a pump discharging through an orifice meter and control valve, but this method is not positively controllable, for varying discharge pressures from the 20 pump give varying flow through the control valve. Even the orifice meter is not an accurate measure of flow, due to foreign matter varying the orifice. This also effects the efficiency of a control valve 25 and constant adjustment is necessary and this results in flow fluctuations.

I have invented an apparatus by means of which liquids can be mixed with liquids, and liquids can be mixed with gases continuously and accurately and the proportions can be controlled as to desired percentages without the aid of a direct feed 30 pump. As an example, if an oil is being charged to a treating unit by means of a pump or by pressure, no direct pump or pressure will be required upon the acid in order to properly proportion 35 and feed it into the treating unit.

The principle on which my invention is based may be briefly stated as follows:

If one of two commodities being proportioned is 40 being charged to the apparatus under pressure through an ejector or Venturi tube, another commodity can be forced into the apparatus by the power set up by the ejector or Venturi tube, and if the flow of the commodity under pressure is constant, the power of the ejector or Venturi tube 45 is also constant, and the flow of the second commodity will be constant provided its differential head with reference to the ejector is constant. By means of my invention I am able to regulate this 50 head and thus to change the desired percentage of the second commodity.

In order to more fully explain my invention, I have illustrated a simple outline of apparatus in which the invention is embodied and which I will now describe.

55 Figure 1 is a vertical sectional view through an

apparatus embodying my invention; and Figure 2 shows an example of an operating chart.

Referring in detail to the drawing, the acid supply, or the supply of any fluid, to be mixed with another liquid or fluid, is from a tank or reservoir 5, which can be of any suitable size and material, depending upon the fluid used, with a supply pipe 6, and a control valve 7, with operating float 8, for maintaining a definite or predetermined level of the fluid in the supply reservoir 5. Said reservoir is also shown as provided with an outside level gauge 9 for indicating the level in inches.

From said reservoir 5 extends a flow pipe 10, connected with three vertical risers, 11, 12 and 13, each provided with a control valve, as 11', 12' and 13', for controlling the supply of the fluid with which the mixture is to be made. These risers connect at their upper ends with a common pipe 14, connected with the receiving tank or reservoir 15. Control valves 11', 12' and 13' are also connected into said risers, as clearly illustrated. Said risers are in the form of Venturi tubes, having the restricted passages at 16, 17 and 18.

Within each of said risers 11, 12 and 13, discharge pipes or nozzles 19, 20 and 21 are placed, as indicated, connected with the flow pipe 10, whereby the fluid to be mixed with the second fluid flows up into the said nozzles 19, 20 and 21 to the fluid level of the reservoir 5, as indicated.

In the operation of the apparatus, the level of the fluid in the tank or reservoir 5 is maintained and controlled by the float controlled valve 7, and this level is also maintained in the discharge nozzles, as indicated in 19, which is shown in section. The second fluid is supplied through the three vertical risers 11, 12 and 13, and around said nozzles 19, 20 and 21, said nozzles terminating in the Venturi tube portion, as at 16, 17 and 18, as clearly indicated. It will be seen that by changing the differential head between the ejector nozzle and the second fluid, the desired percentage of the second fluid can be mixed with the first fluid and it can thus be controlled.

In the treatment of petroleum with sulfuric acid, the oil is pumped to the treating unit under pressure, as through the vertical risers 11, 12 or 13, as may be desired, one or more at a time through pipe 14 into the tank 15. In the showing made for descriptive purposes, the sulfuric acid is supplied through the nozzles 19, 20 and 21, from the supply reservoir 5, and the level is maintained according to the adjustment of the float valve and float connection, said level

being indicated by the line L. The level is indicated in inches on the gauge 9, as before referred to and the predetermined level in the reservoir 5 regulates or controls the amount of acid or other fluid taken into and up through the vertical risers by the forced flow of petroleum, or other fluid being forced into the receiving tank 15. If, for example, so many barrels of petroleum are being forced through the supply pipes or risers 11, 12 and 13, and pipe 14, into said receiving tank 15, per hour, the amount of acid entrained and carried therewith into said tank 15 will depend upon the level of the acid in said nozzles 19, 20 and 21, and this is controlled by the 10 float adjustment, or any other suitable means for maintaining a predetermined or constant level of said acid or other fluid or liquid.

If a large volume of petroleum is being forced through the pipes 11, 12 and 13, to the receiving 20 or mixing tank 15, the flow will be uniform, but should it vary slightly, the power of the ejector varies accordingly and the entraining action also varies, and the amount of acid carried into the main flow is thereby automatically controlled by 25 reason of the automatic maintenance of a predetermined level. The arrangement shown for explanatory purposes is simple and practical and there is nothing to clog or to get out of order. While I have shown a plurality of risers or supply pipes for one fluid under pressure and these are shown connected in multiple, it will be understood that other connections and other arrangements can be used according to the requirement and that plural connections can be made for 30 the fluid or fluids which are to be mixed proportionally with any given fluid being supplied under pressure to the receiving tank. It will also be understood that any type of ejector, jet pump, Sprengle pump or other arrangement 35 whereby the forced flow of one fluid can entrain another fluid can be used, and that any means for maintaining a predetermined or constant level of fluid to be so entrained can be used and comes within the scope of my invention. I do not therefore, limit my invention to the showing made, except as I may be limited by the hereto appended claims.

I claim:

1. An apparatus for proportionally mixing a 50 petroleum oil with a liquid reagent which includes, a reservoir for the liquid reagent, means for maintaining a predetermined level of said reagent therein, a vertical discharge nozzle connected with said reservoir and in which said

reagent rises toward the outlet end thereof, and means for maintaining a forced flow of petroleum oil under pressure in entraining relationship to said nozzle to cause a flow of the reagent from the nozzle, whereby a proportional mixing takes place which is automatically controlled and maintained substantially constant by the maintained level of the reagent in the reservoir and the quantity flow of the petroleum oil. 80

2. An apparatus for proportionally mixing a 85 petroleum oil with a liquid reagent which includes, a reservoir for the liquid reagent, means for maintaining a predetermined level of said reagent therein, a vertical discharge nozzle connected with said reservoir and in which the reagent rises toward the outlet end thereof, a Venturi tube through which the petroleum oil is forced, the outlet end of the discharge nozzle being positioned in said Venturi tube, and means for connecting a supply of petroleum oil under pressure to said Venturi tube. 90

3. An apparatus for proportionally mixing 95 petroleum oil and a liquid reagent which includes, a reservoir for the liquid reagent, adjustable means for adjusting the level of the reagent in the reservoir to any desired position to adjust the relative proportions of the petroleum oil and liquid reagent in the mixture and to automatically maintain the reagent at the adjusted level, a vertical discharge nozzle connected with said reservoir and in which the reagent rises toward the outlet end thereof, a Venturi tube through which the oil is forced, the outlet end of the nozzle being positioned in said Venturi tube, and means for connecting a supply of the oil under pressure to said Venturi tube, whereby the flow of oil through said Venturi tube entrains the reagent from said nozzle proportioned according to the adjusted level of the reagent in the reservoir. 105

4. A method of proportionally mixing oil and a reagent which comprises placing the reagent in a tank in communication with a vertically extending nozzle, forcing the oil under pressure in entraining relation to said nozzle to draw said reagent from the nozzle and mix it with the oil, adjusting the level of the reagent in the tank and the nozzle to adjust the relative proportions of the oil and reagent in the mixture, and automatically maintaining the reagent at the adjusted level to automatically maintain the proportions of the oil and reagent substantially constant. 115
